UNITED STATES PATENT OFFICE.

LLOYD I. WILMANS, OF DALLAS, TEXAS.

LINER FOR TYPOGRAPHICAL CASTING MACHINES.

Application filed April 10, 1922. Serial No. 551,035.

To all whom it may concern:

Be it known that I, LLOYD I. WILMANS, a citizen of the United States, residing at Dallas, in the county of Dallas and State of Texas, have invented certain new and useful Improvements in Liners for Typographical Casting Machines, of which the following is a specification.

This invention relates to new and useful improvements in liners for typographical casting machines.

As is well known the length of a slug depends upon the width of the column in which it is to be set, and as the columns vary in width it is customary to lengthen and shorten the mold slot by removing the liner and inserting another either longer or shorter. An ejector blade of a width substantially the same as the length of the slug is employed to expel the slug from the slot. Under ordinary practice it is necessary to change the ejector blade when a liner is changed, particularly when a longer liner for casting a shorter slug is substituted. It frequently happens that the operator forgets to change the ejector blade and consequently the liner is destroyed and the expensive mold is often broken.

Another source of trouble arises from the variance in the temperature of the molten metal. These changes which are well known, cause the casting of slugs with defective bottoms or slugs which are hollow. When such conditions exist both the ejector blade and slug have a tendency to bind in the mold, whereby the slug becomes stuck and must be removed before the operation of the machine can be continued. These occurrences are frequent and, of course, cause a great loss of time, as well as damaging the liners.

A frequent result is a bent liner with its face extending outwardly from the face of the mold and the back of the liner lying within the marginal edge of the slot. This permits the metal to flow in behind the liner, thus producing a flash on the slugs which must be trimmed off. The face of the liner extending will interfere with the positioning of the matrices with relation to the mold and cause the casting of defective slugs.

The object of my invention is to provide a liner which is arranged to swing outwardly from the mold slot from a pivot or hinge

point, so that it will not be injured or destroyed when struck by the ejector blade and one which will also save said blade from injury.

Another object is to provide a liner capable of undergoing a slight longitudinal movement, whereby contact with a stuck slug is relieved and the liner permitted to swing slightly forward. The pressure on the end of the slug thus being relieved, the ejector will easily push out the slug without injury to the liner, mold, ejector blade or slug.

A further aim of the invention is to provide a hinged or pivoted liner which if displaced from the mold slot, may be readily swung back into the slot. The invention also contemplates the use of an extension link and by use of links of different lengths, to provide numerous adjustments with each liner, thus varying the length of the slug slot accordingly.

An important advantage of the invention is the provision of a liner that is practically indestructible and of long life. By employing such a liner the usual stock of liners may be greatly reduced, likewise the investment. A great saving in time will be had as well as a reduction in repairs and the cost of maintenance of the machine. Further frequent delays will be entirely eliminated and the capacity of the machine increased.

A construction designed to carry out the invention will be hereinafter described together with other features of the invention.

The invention will be more readily understood from a reading of the following specification and by reference to the accompanying drawings, in which examples of the invention are shown and wherein:

Fig. 1 is a perspective view of a mold equipped with a liner constructed in accordance with my invention.

Fig. 2 is a plan view of the mold with the cap detached and illustrated the manner in which an ejector of too great a width swings the liner out of the mold.

Fig. 3 is a plan view of the liner combined with an extension link,

Fig. 4 is an end elevation of the stub to which the liner is hinged,

Fig. 5 is a view similar to Fig. 2, showing a modified form of liner, and

Fig. 6 is a perspective view of said modified liner.

In the drawings the numeral 10 designates the body of a typical casting machine mold 5 and 11 the cap of the same. At one end of the mold a spacer 12 is interposed between the body and cap. A liner 13 is interposed between the body and cap at the opposite end and the mold slot 14, is thus formed between the parts 12 and 13. The length and thickness of this is varied by changing the liners. An ejector blade 15 is adapted to enter the slot and eject the slug therefrom.

The invention has to do with the liner, 15 which it is to be understood may be pivoted in any suitable manner so as to swing outwardly and to be again swung inwardly, without injury and under certain conditions without loss of time.

20 In one form of liner I provide a liner stub or small plate 16 which has a transverse recess 17 receiving the stud 18, which is present on linotype machines. The body 10 has a transverse groove 18' on its upper face 25 which receives a rib 19' depending from the stub. The liner blade 13 has a hook 20 projecting longitudinally from the outer corner of the inner end, said hook having a depending boss 21.

30 The stub has its front or transverse edge cut back at 22 except for a portion at its base and is formed at its inner corner with a lug 23 at the base of an inclined edge 24. The boss 21 engages over the lug and rests 35 upon the inclined edge. The engagement of the hook with the lug forms a pivot or hinge joint, whereby the liner blade may be swung outwardly. The edge 22 permits the liner blade to undergo a slight longitudinal movement at the start of its swing, thus relieving any pressure upon a slug which might be stuck. It will be seen that as the liner 40 swings outwardly the boss 21 rides up the inclined edge 24, as is illustrated in Fig. 2. The depth of the cut of the edge 22 is exaggerated in the drawings for the purpose 45 of illustration. The stub 16 and blade 13 constitute the complete liner.

In Fig. 3 I have shown another form in 50 which an extension link 30 is included in the liner and is interposed between the stub and blade. The link has a cut back edge 22', a lug 23', an inclined edge 24' and a hook 20' provided with a boss 21'. These 55 parts are similar to those of the blade and stub. The hook 20 of the blade is engaged with the lug 23' and the edge 24' of the link; while the hook 20' of the latter is engaged with the lug 23 and edge 24 of the 60 stub. By interchanging blades and links of various lengths, numerous lengths of liners may be had. The blade swings from the link when engaged by the ejector blade 15.

In Figs. 5 and 6, I have illustrated another 65 form of the invention in which the stub and

blade are combined in an integral liner 13' which has an enlarged recess 17' to receive the stud 18. The inner end of the liner has a cut back edge 31 merged into a rounded corner 32. The mold body has a stud 11' at 70 one end and the pivoted end of the liner lies contiguous to this stud. When the liner is swung the edge 32 and the recess 17' permit the liner to shift away from the slug slot. The rounded corner lends freedom to the 75 swinging of the liner.

It is obvious that many forms of pivot or hinge joints may be evolved and those illustrated are merely exemplifications which have proved satisfactory. The liners may be 80 made of hard metal if desired, thus not being easily bent or fractured and capable of long usage; or they may be made of soft metal and capable of being fractured or broken if caught in a vital part which would be 85 damaged by a hard metal liner.

When the ejector blade operates the mold is in a perpendicular position, the free end of the liner being lowermost, and the hinged end being at the top. If the liner has not 90 been changed and the blade 15 strikes the same either the liner blade 13 or the integral liner 13' will be swung outwardly and upwardly. This protects the parts from injury and the liner may be swung back into 95 the slot by the operator.

In the case of a stuck slug the cut back edges 22 or 31 will allow the liner to move upwardly and the hinge joint will permit it to move slightly outwardly, and the stuck 100 slug is released. The liner is not swung outwardly far enough to lock the machine and will be engaged by the matrix holding jaws at its next operation and automatically swung back into place. The liner is thus 105 not injured and no time is lost in replacing the same or removing stuck slugs by hand.

As the liner is always returned to its position either manually or automatically before the next slug is cast, and as said liner cannot be bent no flash or burrs will be had. Slugs with defective bases will be eliminated. No broken or fractured slugs will be had and the machine will be saved from 110 injury.

In changing liners it is merely necessary to raise the cap and substitute a liner blade 13 or 13' of the proper length to give the desired length to the slot 14. When the link is employed either another link 30 or 120 another blade may be substituted to change the slug slot 14.

What I claim is:

1. A mold liner consisting of a structure having a pivoted joint for permitting 125 a swinging movement outwardly when the liner is engaged by the ejector and inwardly into the mold when the liner is engaged by parts in front of the face of the mold, said structure also being provided with 130

means for allowing it to undergo a limited longitudinal movement during its swinging movement.

2. A mold liner comprising a member pivoted within the mold and having one transverse edge cut back, whereby said member will swing outwardly and undergo a longitudinal movement to release stuck slugs, whenever engaged by an ejector.

10 3. A mold liner comprising a member having a pivot joint constructed to permit a longitudinal as well as swinging movement of the member.

15 4. A mold liner comprising a stub, and a liner blade pivoted to the stub, there being sufficient play at the pivot to permit the member to move longitudinally as it swings.

20 5. A mold liner comprising a stub having a lug, a liner blade having a hook engaging over the lug, whereby the blade is hinged to the stub.

25 6. A mold liner comprising a stub having a cut back edge and a lug, and a liner blade having a hook engaging over the lug, the end of the blade under the hook being spaced from the cut back edge of the stub and the outer edge of the stub being inclined from

the lug, whereby the blade may undergo a longitudinal movement during its swinging movement.

30 7. A pivoted mold liner comprising a structure having a recess cut in one edge to engage a stud in a mold slot and having one end cut back to permit longitudinal movement.

35 8. A mold liner comprising a stub adapted to engage in a mold slot, a link detachably connected with a stub, and a liner blade pivoted to the link, the pivot connection having sufficient play to permit the blade to undergo a longitudinal movement during its swinging movement.

40 9. A mold liner comprising a stub having a recess for engaging a stud in a mold slot and having its transverse edge cut back, a lug at the outer end of the cut back edge, the outer edge of the stub being inclined from the lug, a liner blade pivoted to the stub by a hook having a boss engaging over the lug and resting on the inclined edge of the stub.

45 In testimony whereof I affix my signature.

LLOYD I. WILMANS.
